UNITED STATES PATENT OFFICE

HARRY EHLIG, OF PEARL RIVER, NEW YORK, ASSIGNOR, BY MESNE ASSIGNMENTS, TO DEXTER FOLDER COMPANY, OF NEW YORK, N. Y., A CORPORATION OF NEW YORK

SHEET FEEDER

Application filed May 29, 1923. Serial No. 642,189.

My invention relates to improvements in sheet feeders for automatically separating and advancing successive sheets of paper or other impression-receiving material to printing, folding or ruling machines, or to such other types of machines as are devised to operate thereafter on such sheets.

The objects of my invention are, among other things, mainly to provide a sheet-feeder of this character having a simplified design which will have embodied therein separate mechanisms capable of performing efficient work, while they are not likely to get out of order, yet are very sensitive in action, all being incorporated in a feeder which will invariably separate and continuously feed or advance the successive sheets, preferably from a fanned-out bank of paper on the feed-board, both automatically and with great rapidity.

With this aim in view I have devised a front-edge feeder which will separate and advance the successive sheets by mechanism or devices operating on the front edges or margins of the stacked-up sheets, the sheet forwarding mechanisms for the bank of sheets being controlled by the steady and continuous advance of the front margins of the pile or bank of paper supported on the feed-board beneath the feeding-off devices.

A further feature of my invention is to embody in the feeder a novel and improved form of suction feeding-off device which is usually arranged in pairs across the feeder for successively separating and feeding the sheets forwardly, the operation of each set being controlled by a separate cut-out or trip finger located between the usual feed rolls which finger not only limits the forward movement of the particular suction feeding-off device but also cuts off the suction from such device at a predetermined point to release the advancing sheet. Each suction device operates independently of the other so as to straighten the leading edge of the ad-

vanced sheet as it is seized by the feed-rolls.

Another feature is to provide a novel and simplified pile detector mechanism which operates in conjunction with means for smoothing out the front margins of the successive sheets as they are fed forwardly, which will also operate independently of the suction feeding-off devices, and also independently of the number of timing of the sheets advanced thereby, so as to inaugurate and control the action of the bank feed or pile feed mechanism by which the sheets of paper may be advanced and maintained at the proper thickness beneath the suction feeding-off devices operating on the front margins of the sheets, all through the continued operation of the sheet-feeder itself.

A further object of my invention is to provide a novel form of adjustable tail clamp and pile drag which may be set at different positions to bear on the rear margins of the fanned-out sheets of different sizes, and is constructed and arranged above the feed-table to rest on the rear margin of the top sheet of the bank at the beginning of the feed and then upon the rear margin of the second subjacent sheet. Such devices are so constructed and arranged as to be self-adjusting as to the thickness of the bank, and have embodied therewith air-blast devices impinging on the rear edges of the fanned-out top sheets which serve to inject the desirable air films between the sheets to aid in their separation transversely along their rear margins; such devices are particularly located so as to maintain the rear edges of the top sheets in proper alignment with a light yet firm pressure which is not only provided with means for ready adjustment to suit different grades and weights of paper, but also will not interfere in any way with the successive feeding of the sheets.

My improved sheet-feeder also embodies other advantageous features of novelty and improvement in which the different operat-

50

55

60

65

70

75

80

85

90

ing parts are greatly simplified in form, arrangement and interaction, and are made more effective and otherwise better adapted for use, all of which will be hereinafter described and then particularly pointed out in the appended claims.

The accompanying drawings show my improvements in their preferred embodiment in a continuous sheet-feeder; such improvements, however, are not to be restricted to any particular type of sheet-feeder, as these features of invention may be embodied in various forms of feeders with similar advantages and results.

15 Of the drawings, Fig. 1 is a side elevation looking from the left in Fig. 2, certain parts being omitted, but showing a side view of the combined tail clamp and pile drag resting on the bank of sheets supported on the feed-board;

Fig. 2 is a front elevation of the feeder with the central parts broken away;

Fig. 3 is a sectional view taken on the line 3—3 of Fig. 2 looking in the direction of the arrow;

Fig. 4 is a sectional view taken on the line 4—4 of Fig. 2 looking in the direction of the arrows;

Fig. 5 is a detail sectional view on an enlarged scale taken on the line 5—5 of Fig. 3 looking in the direction of the arrow;

Fig. 6 is a central longitudinal section of the clamp and pile drag mechanism to operate on the rear margins of the sheets;

35 Fig. 7 is a top plan view of the mechanism shown in Fig. 6; and

Fig. 8 is a detail rear elevation of such mechanism.

Similar numerals refer to similar parts 40 throughout the several figures.

Referring more particularly to Figs. 1-4, the two side-frames 7 and 8 of the feeder proper are supported upon the standards 9 and 10 respectively; between the side-frames 45 7 and 8 and suitably secured thereto is the lower feed-board 11 over which travel a series of feed belts 12 to advance the fanned-out bank of sheets 13 along the feed-board 11. The belts 12 (two being shown in Fig. 2) pass 50 around the drum 14 mounted on the transverse shaft 15 journalled in suitable bearings in the frames 7 and 8. The shaft 15 carries the ratchet 16 by which the feed-belts 12 are intermittently advanced over the feed-board 55 11 to carry the bank of fanned-out sheets 13 to the sheet separating and feeding-off devices arranged across the front edge of the feed-board 11.

In the present embodiment of my feeder, 60 the sheet separating and advancing devices are duplicated upon either side of the machine, and a description of one set of such devices will therefore suffice, as both sets are built and operate alike. Referring more particularly to Figs. 2, 3 and 5, the carriage plate

17 is adjustably secured to the tie-shaft 18 by the split-collar 19 and clamping bolt 20 so that the carriage 17 may be transversely shifted in the feeder to accommodate sheets of different widths. The upper bracket 21 70 of the carriage 17 carries the collar 22 within which is journalled the main cam-shaft 23 which extends across the feeder and is suitably supported in bearings in the side-frames 7 and 8 as shown in Fig. 2. This shaft 23 has secured thereto the gear 24 which engages the pinion 25 mounted on the stub-shaft 26 journalled in the side-frame 7, the shaft 26 also carrying the gear 27 enmeshing with the idler gear 28 which is driven by the pinion 29 80 fast to the main power shaft 30 which is suitably journalled in the side-frames 7 and 8, the arrows shown in Fig. 3 indicating the respective directions of revolution of the several gears to rotate the cam-shaft 23 in a 85 clockwise direction.

Extending across the feeder and suitably journalled in the side-frames 7 and 8 is the rock-shaft 31 to which is slidably secured the sleeve 32 by the key 33 to rock with the shaft 90 31. Loosely secured on one end of the sleeve 32 and rotatably mounted in the carriage 17 is the oscillating suction feed-sector 34, and surrounding the sleeve 32 is the coil spring 35, one end of which is fastened to the collar 36 pinned to the sleeve 32 and the other end is fixed to the pin 37 on the feed-sector 34 as shown in Fig. 2. The tension of the spring 35 normally forces the sector 34 forwardly. The segmental rim 38 of the feed-sector 34 95 carries the spaced-apart perforations 39 preferably arranged in staggered relation as shown in Fig. 2; the suction mouthpiece 40 with its nozzle 41 bears on the inner face of the perforated rim 38, and is held in position by the hollow arm 42 attached to the transverse suction tube 43 secured in the side-frames 7 and 8. The nozzle 41 is arranged to register intermittently with the successive perforations 39 in the feed-sector 34 as the latter swings forwardly. The required suction to operate the feed-sector 34 100 is applied to the tube 43 by any suitable air-exhausting means not shown. The sheets from the bank 13 adhere to the exterior surface of the rim 38 opposite the nozzle 41 as shown in Fig. 3, and are separated and advanced to the bite of the lower feed-rolls 44 and coacting upper feed rolls 45.

The feed-rolls 44 are rotatably mounted on the shaft 30, while the feed-rolls 45 are secured to the cross-shaft 46 journalled on the arms 47 of the bell-crank lever 48 pivotally mounted to the cross shaft 49 journalled in the side-frames 7 and 8; the upper arm 50 of the lever 48 carries the cam-roller 51 which rides on the cam 52 mounted on the cam-shaft 23. The coil spring 53 pinned to the arm 47 and to the side frame 7 causes the upper feed rolls 45 to contact with the driven 125 130

lower feed-rolls 44 in timed relation to seize the leading edge of the sheet when the cam-roller 51 enters the drop of the cam 52, the arrangement shown in Fig. 3 showing the roll 45 in raised position with the cam roller 51 riding on the dwell of the cam 52.

The rock-shaft 31 is intermittently oscillated forwardly to rock the sleeve 32 and release the feed-sector 34 held under tension 10 of the spring 35 to advance the adhering sheet in proximity to the bite of the feed-rolls 44 and 45 by the following described mechanism: The shaft 31 carries the arm 54 connected by the link 55 with the arm 56 of the bell-crank lever 57 rotatably mounted on the shaft 15. Pivotedly connected to the lever 57 is the link 58 carrying on its end the cam-roller 59 to engage the cam 60 fixed to the cam-shaft 23. The link 58 is formed with the intermediate slot 61 through which passes the shaft 23 to support link 58 on the shaft 23, and permit its movement by the cam 60. Secured to the lever 57 is the arm 62 which is normally forced upwardly by the 25 compression spring 63 (Figs. 2 and 3) to hold the cam-roller 59 in engagement with the cam 60 which releases the feed-sector 34 to swing forwardly when the roller 59 descends into the drop of the cam 60, and retracts the sector 34 and places the spring 35 under tension 30 as the roller 59 rides up on the dwell of the cam 60. The relative positions of the cams 52 and 60 are such that as the sector 34 is ending its forward stroke the feed roll 45 is lowered into contact with the feed-roll 44 to seize 35 the leading edge of the sheet which has been separated and fed forwardly by the sector 34.

Means are provided to arrest the forward stroke of the feed-sector 34 and likewise to 40 shut off the suction from the nozzle 41 immediately upon the seizure of the sheet by the feed-rolls 44 and 45, which mechanism may be widely varied in structure and operation. In the present embodiment the lower 45 bracket 64 of the carriage 17 carries the screw-pin 65 which in turn supports the cut-out or trip finger 66, the forward end being forked with the tips 67 riding in parallel grooves 68 formed in the underlying feed- 50 roll 44 as shown in Figs. 2 and 5. The finger 66 is screwed to the supporting plate 69 carried by the collar 70 pivotally mounted on the pin 65 as shown in Figs. 3 and 5; projecting rearwardly from the collar 70 is the 55 latch-arm 71 with its triangular-shaped tip 72 held adjustably by the light spring 73 in engagement with the lower arm 74 of the pawl 75 pivoted on the hub 76 fast in the bracket 64. The coil-spring 77 secured to the 60 arm 74 and the carriage 17 normally pulls the arm 74, when released from the latch-arm 71, to the right in Fig. 3 to lift the pawl 75 into engagement with the segmental rack 78 affixed by screws to the feed-sector 34. By 65 this mechanism the forward swing of the

feed-sector is arrested and immediately ceases when the advanced sheet through the trip finger 66 releases the pawl 75 to engage the teeth of the rack 78, while the rock-shaft 31 and sleeve 32 complete the forward 70 oscillation as the cam-roller 59 follows the drop in the cam 60, and the finger 66 is slightly raised from the sheet.

Referring to Figs. 2, 3 and 5, the sleeve 32 carries at one end the curved rock-arm 79 75 projecting downwardly and forwardly from the shaft 31, and also the rock-arm 80 extending rearwardly as shown particularly in Fig. 3. The arm 79 carries the lug 81 on the outside and adjustably supports the screw-threaded stop-pin 82 which engages with the projection 83 carried by the hub 76. When this arm 79 is rocked in an anti-clockwise direction as the cam-roller 59 rides out of the drop of the cam 60, the pawl 75 is thereby disengaged from the rack 78, and the arm 74 is swung forwardly over the tip 72 of the latch-arm 71 against the tension of the spring 77 to reset the latch-arm 71 as shown in Fig. 3.

The mechanism to shut off the suction from mouth-piece 40 after the forward movement of the feed-sector 34 is arrested by the engagement of the pawl 75 with the rack 78 in the present embodiment is best shown in 95 Figs. 2, 3 and 5. The inner side of the mouth-piece 40 has cut therein the port 84 which is opened and closed by the swinging valve plate 85 integral with the sleeve 86 pivotally mounted on the screw-pin 87 secured to the bracket 88 formed on the top of the mouth-piece 40 as shown in Fig. 5. Secured to the sleeve 86 are the arms 89 and 90, the arm 89 devised to contact with the adjustable screw pin 91 threaded in the bracket 92 mounted 100 on the rock-arm 79, while the arm 90 is arranged to coact with the adjustable screw-pin 93 threaded in the end of the rock-arm 80. When the forward movement of the feed-sector 34 is arrested by the pawl 75 engaging the teeth of the rack 78, the pin 93 having been properly adjusted in the rock-arm 80 thereafter engages the arm 90 to swing the valve-plate 85 which opens the port 84 to atmosphere and cuts off the suction from the mouth-piece 40 and nozzle 41 and releases the sheet adhering to the rim 38. In like manner the port 84 is closed by the valve 85 and suction pressure again maintained in the mouthpiece 40 when the rock-arm 79 is 110 oscillated in a clockwise direction so that the pin 91 engages the arm 89 to swing the valve 85 into its closing position. The positions of the pins 91 and 93 are so adjusted with relation to the arms 89 and 90, that the port 84 is opened slightly after the arrest of the forward movement of the feed-sector 34 by the pawl 75 engaging the rack 78, and the port 84 is closed when the sector 34 is being 120 retracted as the sleeve 32 is oscillated as the 130

roller 59 rides out of the drop of the cam 60. By these mechanisms the release of the advanced sheet from the feed-sector 34 is synchronized with the arrest of its forward movement by the pawl 75 restricting the swing of the feed-sector 34, the operation of this mechanism being controlled by the releasing of the latch members 71 and 72 when the leading edge of the advanced sheet raises the trip finger 66, all during the continued operation of the feeder.

The front edges of the sheets comprising the bank 13 are kept separated by a blast of air from the nozzle 94 mounted on the pipe 95 connected with any suitable air pump not shown; the sheets then pass over the guide plates 96 (Figs. 3 and 4) mounted on the tie rod 97, the plates 96 having curved extensions 98 upon which the front margins of the sheets rest (Fig. 3) at the forward end of the feed-board 11.

The detector mechanism which controls and inaugurates the action of the bank feed independently of the successive feeding movements of the oscillating feed-sector 34 in advancing the sheets from the bank 13 is best shown in Figs. 2 and 4. Such mechanism comprises the detector finger 99 suitably mounted in the sleeve bracket 100 pivoted to the pin 101 secured to the end of the rock-lever 102 mounted on the stub-shaft 103 affixed to the side-frame 8 (Fig. 4). The arm 104 of the lever 102 carries the cam-roller 105 held in engagement with the cam 106 on the cam-shaft 23 by the expansion spring 105^a coiled about the rod 105^b pinned to lever 102. When the roller 105 rides on the dwell of the cam 106 in the position shown in Fig. 4, the finger 99 is retracted with its tip raised slightly above the top sheet by the hub 100 engaging the rounded projection 107 of the forked rock-shoe 108 pivoted on the shaft 109 secured to the side-frame 8 (Fig. 2); when the cam-roller 105 falls into the drop of the cam 106, the finger 99 is moved forwardly over the top surface of the sheets, and the rock-shoe is lowered on the front margins to smooth out as well as to hold the front margins of the sheets lightly in position, since the adjustable screw-pin 110 threaded in the lug 111 integral with the shoe 108 follows the lever arm 102 until such lug 111 engages the stop-pin 112. In like manner the backward swing of the arm 102 when the roller 105 rides out of the drop of the cam 106 raises the shoe 108 to the position shown in Fig. 4, while lifting the tip of the finger 99 slightly above the top sheet on the bank.

As shown in Fig. 4, the guide plate 96 is formed with an intermediate slot 113 through which projects the vertical arm 114 of the latch-lever 115 pivoted to the stub shaft 116 secured to the side-frame 8 (Fig. 2). The upper face 117 of the arm is flat

and inclined forwardly in the plane of the guide-plate 96 with the notch 118 centrally cut therein in alignment with the detector 99, as shown in Figs. 2 and 4. Also as shown in Fig. 4, this notch 118 is normally covered by the leading edges of the top sheets of the bank 13 (in the embodiment shown in Fig. 4 by two sheets) which prevent the finger 99 from entering the notch 118. The arm 114 is returned to its vertical position (Fig. 4) by the force of the spring 119 coiled about the rod 120 pinned to the arm 114, the outer end of the rod 120 passing slidably through the bracket 121 secured to the frame 8, the spring 119 being held under compression by the threaded collar 122 screwed on the rod 120. Secured to the shaft 116 is the laterally-extending latch-arm 123, having the shoulder 124 cut therein to engage with the triangularly-shaped block 125 pinned to the end of the lower arm 126 of the bell crank lever 127 rotatably mounted on the shaft 15. The short arm 128 carries the spring pressed pawl 129 which coacts with the ratchet 16 fast on the shaft 15, while the longer arm 130 of the lever 127 carries the cam-roller 131 to engage the cam 132 secured to the shaft 23. Depending from the pin 133 on the arm 130 is the rod 134 which slides through a hole in the bracket 135 secured to the frame 8; between the bracket 135 and the collar 136 adjustably secured to the rod 134 is the expansion spring 137 coiled about the rod 134. Fig. 4 shows the position of the pawl 129 when the cam-roller 131 is riding upon the dwell of the cam 132 with the spring 137 under compression. When the sheets in the bank 13 become depleted so that the front edges of the top sheets fail to cover the notch 118, the detector finger 99 enters and engages this notch on its forward stroke and thereby swings the arm 114 to the left which releases the latch arm 123 from the block 125; this release of the latching members allows the arm 126 to swing to the left when the cam-roller 131 arrives at the drop of the cam 132 through the force of the spring 137. This rocking movement of the bell crank lever 127 in a clockwise direction retracts the pawl 129 over several teeth of the ratchet 16, and when the cam-roller 131 rides out of the drop of the cam 132, the ratchet 16 is rotated in an anti-clockwise direction to advance the feed-belts 12 to forward the bank of sheets until the top sheets thereof again cover the notch 118, and the arm 114 impelled by the spring 119 resumes its vertical (Fig. 4) position to reset the shoulder 124 of the latch-arm 123 into engagement with the block 125 as shown in Fig. 4. The timing of the cams 106 and 132 is such that detector finger 99 has completed its forward stroke to release this latch-arm 123 just before the drop in the cam 132 is reached

when the cam-roller 131 is free thereafter to fall into such drop preparatory to the forward feed of the bank 13.

My improved form of adjustable tail lamp 5 and pile drag which also carries an air blast to wind the rear edges of the sheets may be arranged at different positions to bear on the rear margins of the bank of sheets and is shown in Figs. 1, 6, 7 and 8. Extending rearwardly from the tie-shaft 18 and secured thereto by set-screws 138 are two supporting bars 139 (only one being shown for the sake of clearness) having the racks 140 cut in their top surfaces. Slidably mounted on the bars 15 are split supporting collars 141 having top bearings 142 in which is journaled the short shaft 143 which carries the gear 144 enmeshing with the rack 140; the handle 145 secured to the shaft 143 enables the operator 20 to shift the collars 141 on the bars 140 in either direction as required. The clamping-bolt 146 threaded in the lugs 147 locks the collars 141 in any predetermined position. The collars 141 are provided with depending 25 brackets 148 connected by cross-shaft 149. Supported by the shaft 149 is the carriage 150 having spaced-apart vertical arms 151 centrally slotted at 152 within which slots 152 extends the cross-shaft 149. Secured to 30 the shaft 149 between the arms 151 is the sleeve 153 carrying the projecting upper pins 154 and also the lower pins 155 to engage the opposite sides of the slots 152 to prevent an undue forward and backward movement of 35 carriage 150, while allowing a free vertical movement of such carriage 150 to the extent of the length of such slots. The lower end of the carriage 150 is forked and the shaft 156 is journaled therein with the roller 157 40 fast to the shaft 156 to bear by gravity upon the bank of sheets 13 as shown in Fig. 1. Pivoted to the shaft 156 on either side of the roller 157 are laterally extended, spaced-apart arms 158 having their forward ends 45 formed with slotted bearings 159 in which are rotatably mounted bearing rolls 160 to rest on the tail end of the top sheet. The arms 158 carry the inclined brackets 161 on the ends of which are removably secured by set 50 screws 162 the pipe ends 163 which are connected by hose 164 with any suitable air-pump not shown. Each pipe end 163 is connected to a spaced-apart tube 165, each having an inclined nozzle 166 contacting with the 55 rear edges of the top sheets in alignment with the bearing rolls 160. Air from the nozzles 166 serves to inject air films beneath the rear edges of the sheets to aid in their separation from the bank by the feed-sectors 34. The arms 158 are connected by the cross-bar 167 on which is mounted the forwardly projecting bracket 168 carrying a cross-pin 169 on which the block 170 is rotatably secured. Passing through a hole in the block 60 170 is the slidable rod 171 to support the pile 65

drag device which yieldingly bears on the end of the top sheet. The forward end of the rod 171 has secured thereto the circular plate 172 from which depend three barrels 173 each encircled by coil springs 174 secured to the plate 172 and projecting beyond the barrels 173 with L-shaped ends 175 which bear lightly and yieldingly on the rear margins of the top sheet as shown in Fig. 1. The points of the spring ends 175 are preferably bent to extend forwardly so as to prevent the possibility of their tearing or otherwise injuring thin or delicate paper stock. Slidably secured on the rod 171 is the ball weight 176 which may be shifted along the rod 171, and then secured in any predetermined position by the set-screw 177 to vary the pressure of the springs 175 on the bank 13 according to the weight and surface texture of the stock in the feeder. The position of the springs 175 relatively to the bearing rolls 160 may be varied by the nut 178 which is threaded on the rear end of the rod 171, and which bears against the washer 179; the coil spring 180 encircling the rod 171 between the block 170 and collar 181 tends to keep this resilient pile drag mechanism extended from the block 170, while permitting the springs 175 to be pressed rearwardly if required.

The operation of my sheet-feeder is substantially as follows: When the pair of feed-sectors 34 have picked up the top sheet from the bank 13 as shown in Fig. 3, they swing forwardly in unison with the sheet under the impulse of the coil springs 35 released from compression when the cam-roller 59 falls into the drop of the cam 60 and the rock-shaft 31 is oscillated in a clockwise direction. Whenever the leading edge of the advanced sheet lifts either one of the trip fingers 66 in position to be seized by the bite of the feed rolls 44 and 45, the latch-arm 71 is drawn down to release the pawl arm 74 which allows the pawl 75 to engage the rack 78 to immediately arrest the forward stroke of the particular feed-sector 34 which has been tripped, although the sleeve 32 and shaft 31 complete their predetermined oscillations under the influence of the cam 60. By this mechanism the separate trip fingers directly control the length of the forward feed of each feed-sector 34, and the leading edge of the sheet is thereby straightened, if required, when placed in position at the bite of the feed rolls 44 and 45.

As soon as the forward movements of the separate feed-sectors 34 have been arrested by the pawl 75 and rack 78 engagement, the rotation of the sleeve 32 causes the arm 90 to contact with the stop-pin 93 to shift valve 85 to the left (Fig. 3) to open the port 84 thereby also opening the mouthpiece 40 and nozzle 41 to atmosphere which releases the hold of the feed-sectors 34 on the sheet now in position to be seized by the feed rolls 44

130

and 45. When the cam-roller 59 rides out of the drop of the cam 60, the rock-shaft 31 and sleeve 32 are rocked to restore the feed-sectors 34 to their feeding position while the 5 springs 35 are again put under compression for the next forward stroke; during this retractive movement the arm 89 engages with the stop-pin 91 to shift the valve 85 to the right (Fig. 3) to close the port 84 and place 10 the mouthpiece 40 again under suction in readiness for the feed-sectors to take up the next sheet in the succeeding cycle of operations. During this movement each trip-finger latch resets itself by the arm 74 passing 15 over the tip 72 of the latch-arm as herein-before described, and the trip finger 66 will again lower and rest in the grooves 68 as shown in Fig. 3 in readiness for the next advancing sheet. The timing of the cams 53 20 and 60 is such that the feed roll 44 will lower as the sheet reaches the feed roll 45 in the forward feed of the sectors 34.

When the feed-sectors 34 have separated and advanced the top sheets from the bank 13 25 to diminish the thickness thereof so that it becomes desirable or necessary to advance the pile or bank of sheets by moving the feed-belts 12 on the feed-board 11, the detector finger 99 in its forward stroke engages the 30 exposed notch 118 cut in the face of the arm 114 so as to swing the arm 114 forwardly and release the latch arm 123 from engagement with the block 125, whereby the bell-crank lever 127 is rocked in a clockwise direction. 35 This allows the cam-roller 131 to enter the drop of the cam 132 when the latter has rotated sufficiently, and in that part of the cycle the pawl 129 is simultaneously drawn backwardly over the teeth of the ratchet 16. 40 When the bell-crank lever 127 is rocked in an anti-clockwise direction by the roller 131 riding out of the drop of the cam 132, the ratchet 16 rigidly secured to the shaft 15 will advance the feed-belts to forward the bank of 45 sheets. Such bank-feed movement through this pawl and ratchet mechanism will be repeated with each revolution of the cam 132 until the front margins of the top sheets have been advanced to cover the notch 118 so 50 that the detector finger 99 no longer can swing the arm 114 forwardly in each cycle; the spring 119 straightens the arm 114 which enables the latch-arm 123 to reset itself with the block 125 as has been heretofore described. 55 So long as this latch is set the spring 137 is held under compression with the cam-roller 131 riding only on the dwell of the cam 132 and bridging the drop therein. Such detector control and bank-feed mechanism is 60 very delicate and sensitive in action with the coating rock-shoe 108 serving to smooth out the front edges of the sheets as they are advanced to the feed-rolls during each forward movement of the detector finger 99 65 over the front edges of the sheets.

The adjustable tail clamp and yielding pile drag device which I have shown and described in conjunction with continuous air-blasts to wind the rear edges of the top sheets may be shifted forwardly and backwardly 70 over the feed-board 11 on the rack supporting bars 139 as heretofore described. The carriage 150 with its associated parts has a free vertical movement over the bank 13 on which it bears by gravity, while the pins 154 and 155 preclude a canting movement in either direction on the roller 157 while allowing free vertical movement. Furthermore the bearing rolls 160 press yieldingly on the rear edges of the top sheets by being mounted in the slotted bearings 159, while the air nozzles 166 wind such rear edges to ensure proper separation before the feed-sectors 34 advance the top sheet to the feed rolls 44 and 45. Again distinct advantages are attained 75 by the spring pile drag device with the spring ends 175 bearing lightly on the tail ends of the sheets in that I have provided a mechanism for holding the top sheets under variable pressure which may be adjusted within wide 80 limits for different qualities of stock by means of the ball weight 176 as well as the leverage length of the sliding supporting rod 171; experience has shown that such variable spring pressure is a necessary adjunct in a 85 sheet-feeder operating at high speeds with different grades of paper in order to maintain the proper transverse alignment of the rear margins of the sheets on the feed-board 11. 90

The foregoing constructions embody the essential principles of my invention as embodied in a continuous sheet-feeder, but various changes may be made in the structural details without departing from the scope of my improvements. However the foregoing is sufficient to disclose the underlying principles and advantages of my invention as particularly applied to a continuous sheet-feeder. 100

I claim as my invention:

1. In a sheet-feeder, a suction feed-member having suction applied thereto at its lowermost portion and oscillatable forwardly in a vertical plane over the superposed sheets for separating and advancing same and means including a part actuated by the leading edge of the advanced sheet for arresting the forward movement of said member. 115

2. In a sheet-feeder, a movable suction feed-member operating on the front margins of the sheets for separating and advancing the successive sheets, and means controlled by the advanced sheet for arresting the sheet-advancing movement of the member. 125

3. In a sheet-feeder, a movable suction feed-member operating on the front margins of the sheets for separating and advancing 130

- the successive sheets, and means controlled by the leading edge of the advanced sheet for arresting the sheet-advancing movement of the member.
- 5 4. In a sheet-feeder, a movable suction feed-member operating on the front margins of the sheets for separating and advancing the successive sheets, and means controlled by the advanced sheet for arresting the sheet-
10 advancing movement of the member and means for shutting off the suction therefrom.
5. In a sheet-feeder, a movable suction feed-member operating on the front margins of the sheets for separating and advancing the successive sheets, and means controlled by the advanced sheet for sequentially arresting the movement of the member and means for shutting off the suction therefrom.
6. In a sheet-feeder, a movable suction feed-member operating on the front margins of the sheets for separating and advancing the successive sheets, and means controlled by the leading edge of the advanced sheet for arresting the movement of the member and
25 means for shutting off the suction therefrom.
7. In a sheet-feeder, a movable suction feed-member operating on the front margins of the sheets for separating and advancing the successive sheets, and means controlled by the leading edge of the advanced sheet for sequentially arresting the movement of the member and means for shutting off the suction therefrom.
- 30 8. In a sheet-feeder, a suction feed-sector having suction applied thereto at its lowermost portion and oscillatable forwardly in a vertical plane over the fanned-out front top portion of the superposed sheets for advancing the successive sheets forwardly
35 therefrom.
9. In a sheet-feeder, a suction feed-sector having suction applied thereto at its lowermost portion and oscillatable forwardly in a vertical plane over the fanned-out front top portion of the superposed sheets for intermittently separating and advancing the successive sheets forwardly therefrom.
- 40 10. In a continuous sheet-feeder, a rocking suction feed-member for advancing the fanned-out sheets from the front margin of the bank by applying suction thereto throughout the forward stroke of said feed-member.
- 45 55 11. In a continuous sheet-feeder, a rocking suction feed-member for intermittently separating and advancing the fanned-out sheets from the front margin of the bank by applying suction thereto throughout the forward stroke of said feed-member.
- 60 55 12. In a sheet-feeder, a feed-board, means for advancing a pile or bank of sheets along said feed-board, and a movable suction feed-member operating on the front margins of the sheets for intermittently separating and advancing forwardly the successive sheets by applying suction thereto.
13. In a sheet-feeder, a feed-board, means for advancing a pile or bank of sheets along said feed-board, a movable suction feed-member operating on the front margins of the sheets for intermittently separating and advancing the successive sheets by applying suction thereto, and means controlled by the advanced sheet for arresting the forward stroke of the member.
- 70 14. In a sheet-feeder, a feed-board, means for advancing a pile or bank of sheets along said feed-board, a movable suction feed-member operating on the front margins of the sheets for intermittently separating and advancing the successive sheets by applying suction thereto, and means controlled by the advanced sheet for arresting the forward stroke of the member at any part of its movement.
- 80 15. In a sheet-feeder, a pair of movable suction feed-members for separating and advancing the successive sheets and separate means for each feed-member for arresting its sheet-advancing movement.
- 85 16. In a sheet-feeder, a pair of movable suction feed-members for separating and advancing the successive sheets and separate means for each feed-member controlled by the advanced sheet for arresting its sheet-advancing movement.
- 90 17. In a sheet-feeder, a pair of movable suction feed-members for separating and advancing the successive sheets and separate means for each feed-member controlled by the leading edge of the advanced sheet for arresting its sheet-advancing movement.
- 95 100 18. In a sheet-feeder, a pair of movable suction feed-members for separating and advancing the successive sheets and separate means for each feed-member for independently arresting its movement and shutting off the suction therefrom.
- 105 110 19. In a sheet-feeder, a pair of movable suction feed-members for separating and advancing the successive sheets and separate means for each feed-member for sequentially and independently arresting its movement and shutting off the suction therefrom.
- 115 120 20. In a sheet-feeder, a sheet support, a movable suction feed-member arranged above the support to advance the sheets, means for applying suction to the member, and means for shutting off the suction after the sheet has been advanced to its foremost position by said member.
- 125 21. In a sheet-feeder, a sheet support, a movable suction feed-member arranged above the support to advance the sheets, means for applying suction to the member, and latch-controlled means for shutting off the suction after the sheet has been advanced to its foremost position by said sector.
- 130 22. In a sheet-feeder, a sheet support, a

- movable suction feed-member arranged above the support to advance the sheets, means for applying suction to the member, latch-controlled means for shutting off the suction after the sheet has been advanced to its foremost position by said member, and a trip finger actuated by the advanced sheet to release said latch-controlled means. 70
23. In a sheet-feeder, a sheet support, a pair of movable suction feed-members arranged above the support to advance the sheets, means for applying suction to each member, and separate means for independently shutting off the suction from either member after the sheet has been advanced to its foremost position by said sectors. 75
24. In a sheet-feeder, a sheet support, a pair of movable suction feed-members arranged above the support to advance the sheets, means for applying suction to each member, and separate means controlled by the advanced sheet for independently arresting the forward stroke of either member at any part of its movement and sequentially means for shutting off the suction from either member. 80
25. In a sheet-feeder, a gravity tail clamp and an oscillatable pile drag having resilient members having points bearing on the sheets. 85
30. 26. In a sheet-feeder, a gravity tail clamp, an associated air blast impinging on the rear edges of the sheets and an oscillatable pile drag having resilient members having points bearing on the sheets. 90
35. 27. In a sheet-feeder, a gravity tail clamp and an oscillatable pile drag having resilient members having points bearing on the sheets, and means for shifting said devices longitudinally of the feeder. 95
40. 28. In a sheet-feeder, a gravity tail clamp and an oscillatable pile drag having resilient members having points bearing on the sheets, and means for shifting said devices as a unit longitudinally of the feeder. 100
45. 29. In a sheet-feeder, a gravity tail clamp and an oscillatable pile drag having resilient members having points bearing on the sheets, means for shifting said devices longitudinally of the feeder, and means for locking said shifting means in any predetermined position. 105
50. 30. In a sheet-feeder, a gravity tail clamp and an oscillatable pile drag having resilient members having points bearing on the sheets, means for shifting said devices as a unit longitudinally of the feeder and means for locking said shifting means in any predetermined position. 110
55. 31. In a sheet-feeder, a pile drag adjustably mounted to rest yieldingly on a fanned-out bank of sheets and provided with a plurality of vertically disposed spring members having points bearing on the top sheets. 115
60. 32. In a sheet-feeder, a pile drag adjustably mounted to rest yieldingly on a fanned-out bank of sheets and provided with a plurality of vertically disposed spring members bearing on the top sheets, and means independent of said spring members for variably adjusting the pressure of said spring members on the sheets. 120
65. 33. In a sheet-feeder, a pile drag adjustably mounted to rest yieldingly on a fanned-out bank of sheets and provided with a plurality of vertically disposed spring members bearing on the top sheets, and means independent of said spring members for variably adjusting the pressure of said spring members on the sheets. 125
70. 34. In a sheet-feeder, a pile drag adjustably mounted to rest yieldingly on a fanned-out bank of sheets and provided with a plurality of vertically disposed spring members bearing on the top sheets, and means for variably and collectively adjusting the pressure of said spring members on the sheets. 130
75. 35. In a sheet-feeder, a pile drag adjustably mounted to rest yieldingly on a fanned-out bank of sheets and provided with a plurality of vertically disposed spring members bearing on the top sheets, and means independent of said spring members for variably and collectively adjusting the pressure of said spring members on the sheets. 135
80. 36. In a sheet-feeder, a gravity tail-clamp resting on the bank of fanned-out sheets and an air blast arranged adjacent to the clamp to wind the rear edges of the sheets. 140
85. 37. In a sheet-feeder, a gravity tail-clamp resting on the bank of fanned-out sheets and an air blast arranged adjacent to the clamp and in alignment therewith, to wind the rear edges of the sheets. 145
90. 38. In a sheet-feeder, a gravity tail-clamp freely movable in a vertical direction, and means carried thereby to prevent a canting movement longitudinally of the feeder in either direction. 150
95. 39. In a sheet-feeder, a movable suction feed-member, means including a trip controlled by the advancing sheet for arresting the forward movement of the member said means having a part to raise the trip from the advanced sheet. 155
100. 40. In a sheet-feeder, an oscillatable suction feed-member, having suction applied thereto at its lowermost portion for both separating and advancing the sheets, a trip actuated by the leading edge of the advanced sheet for arresting the forward movement of said member, and means for raising the trip from said sheet. 160
105. 41. In a sheet-feeder, an oscillatable suction feed-member, having suction applied thereto at its lowermost portion for both separating and advancing the sheets, a trip actuated by the leading edge of the advanced sheet for arresting the forward movement of said member, and means for thereafter raising the trip from said sheet. 165
110. 42. In a sheet-feeder, a vertically recipro- 170

- cating suction feed member for separating and advancing the fanned-out sheets forwardly from the front portion of the bank.
43. In a sheet-feeder, a reciprocating suction feed member for separating and advancing the fanned-out sheets from the front portion of the bank and means controlled by the advanced sheet for arresting the sheet-advancing movement of said member. 70
- 11 44. In a continuous sheet-feeder, a vertically reciprocating suction feed member operating on the front portion of the fanned-out bank for separating and advancing the successive sheets forwardly therefrom. 75
- 15 45. In a continuous sheet-feeder, a vertically reciprocating suction feed member operating on the front portion of the fanned-out bank for intermittently separating and advancing the successive sheets forwardly therefrom. 80
- 20 46. In a sheet-feeder, a reciprocating suction feed member for separating and advancing the fanned-out sheets from the front portion of the bank and means including a sheet-operated trip for arresting the sheet-advancing movement of said member at any point during said movement. 85
- 25 47. In a sheet-feeder, sheet-controlled suction means oscillatable in a vertical plane over the front top portion of the superposed sheets for separating and advancing same. 90
- 30 48. A sheet feeding machine having, in combination, suction members for separating and advancing the top sheet, and cutouts operated by the front edge of the sheet to arrest the advance of the sheet by said members. 95
- 35 49. In a sheet feeder, a sheet support, a pair of movable suction feed members arranged above the support to separate and advance the sheets, means for applying suction to each member, separate means controlled by the advanced sheet for independently arresting the forward stroke of either member on any part of its movement, and means for shutting off the suction from the members. 100
- 40 50. A sheet feeding machine having, in combination, suction members for separating and advancing the top sheet, driving means for the suction members, yielding means connecting the driving means with the suction members, and means interposed in the path of movement of the advancing sheet for arresting the movement of the members. 105
- 45 51. A feeding mechanism for feeding sheets from the top of a pile comprising an oscillating feeder through which a suctional force is exerted on the topmost sheet, suction means connected with the oscillating feeder and controlled by the fed-off sheet and means for swinging said feeder back and forth about a stationary axis. 110
- 50 52. A feeding mechanism for feeding sheets from the top of a pile comprising a member movable back and forth and having a series of openings through which a suctional force is adapted to be exerted, a stationary member having an opening with which said first-named openings are adapted to register successively and means for moving said member forwardly to feed a sheet and then back through the same path. 115
- 55 53. In a feeding mechanism for feeding sheets from the top of a pile, a feeder member movable back and forth, the return movement being through the same path as the forward movement, and having a plurality of openings through which a suctional force is adapted to be exerted on the top-most sheet, suction means operatively connected to the feeder member, means for alternately moving said feeder member forwardly and rearwardly, and means for causing the suction means to be rendered ineffective during the rearward movements of the feeder member. 120
- 59 54. In a sheet feeding mechanism, an oscillatory feeder member, means for actuating the same so as to give it alternately a forward feeding movement and a return movement, suction means operatively connected with the feeder member about a stationary axis, and means for rendering the suction means ineffective during the return stroke of the feeder member. 125
- 63 55. A sheet feeding mechanism comprising an oscillatory feeder member having a plurality of openings through which a suctional force is adapted to be exerted on the sheet to be moved, means for actuating said feeder member so as to give it alternate feeding and return strokes about a fixed axis, means including a part operatively connected to the feeder so that suctional force is successively exerted on the sheet through the different openings, and means for rendering the suction means ineffective during each return stroke of the feeder member. 130
- 67 56. In a sheet-feeder, an oscillatable suction feed-member having suction applied thereto at its lowermost portion for both separating and advancing the sheets and a trip actuated by the leading edge of the advanced sheet for arresting the forward movement of said member. 135
- 71 57. In a sheet-feeder, a sheet-controlled oscillatable suction feed-member for advancing the sheets and means for swinging said member back and forth about a stationary axis. 140
- 75 58. In a sheet-feeder, a sheet controlled oscillatable suction feed-member and means for moving member forwardly to feed a sheet and then backwardly through the same path. 145
- 80 59. In a sheet-feeder, an oscillatable feed-member swinging on a fixed axis for separating and advancing the sheets, a single mechanism for actuating said member in both directions, and means controlled by the ad- 150

vanced sheet for disengaging said member from said mechanism during the sheet-advancing movement of said member.

60. In a sheet-feeder, an oscillatable feed-member swinging on a fixed axis for separating and advancing the sheets, a single mechanism for actuating said member in both directions, and means controlled by the advanced sheet for disengaging said member from said mechanism during the sheet-advancing movement of said member but allowing an automatic engagement on the reverse movement of said member.
